Des. 197,589
Patented Feb. 25, 1964

197,589

HAIR DRYER

Richard B. Hall, Cincinnati, Ohio, assignor to Dominion Electric Corporation, a corporation of Ohio

Filed June 20, 1963, Ser. No. 75,450

Term of patent 14 years

(Cl. D86—10)

FIG.1

FIG. 2

FIG.4

FIGURE 1 is a perspective view of a hair dryer embodying my design, taken from one angle;

I claim:

The ornamental design for a hair dryer, substantially as shown.
